UNITED STATES PATENT OFFICE.

CLIFFORD G. MILLER, OF NEW YORK, N. Y.

MAGNETIC SWITCH.

1,061,919.

Specification of Letters Patent. Patented May 13, 1913.

Application filed September 19, 1912. Serial No. 721,158.

To all whom it may concern:

Be it known that I, CLIFFORD G. MILLER, a citizen of the United States, and a resident of the city of New York, borough of Manhattan, in the county and State of New York, have invented a new and Improved Magnetic Switch, of which the following is a full, clear, and exact description.

This invention relates to magnetically operated devices, and has particular reference to a device of this character which is adapted for the operation of any element through magnetic influence, said element to be operated in the opposite direction when the magnetism ceases, either by gravity or by some other means.

More specifically, this invention is well adapted for the temporary making of an electric circuit as when the magnetism is caused to operate upon a movable blade or member adapted to bridge the two normally open contact points of such circuit. I wish it to be understood, however, that this particular adaptation of the invention is to be taken as illustrative rather than in a limiting sense.

A preferred embodiment of the invention is illustrated in the drawings accompanying this specification in which like characters of reference indicate corresponding parts in all the views, and in which—

Figure 1 is a front elevation; Fig. 2 is a rear elevation; and Fig. 3 is a vertical sectional view of the invention substantially on the line 3—3 of Fig. 2.

Referring particularly to the drawings I show at 10 a plate or disk of any suitable size or form adapted to be cemented or otherwise secured to one side of a window pane 11 or any other suitable support. The upper portion of the disk may be thicker than the lower portion so that the disk as a whole will have an inclined rear face, although it is to be understood that in this and other particulars the exact form of any of the parts shown need not be adhered to in all instances. Said disk is shown provided at its central portion with an opening 10'. A magnet 12 is shown suspended opposite

said opening in the disk by means of an arm 13 pivotally connected at 14 to the upper part of the disk. By reason of the inclination of the rear face of the disk, the lower end of the arm is normally spaced from the lower portion of the disk, it being carried

to such position by gravitation of the magnet. The lower end of the arm carries a bridge 15 which, in this particular embodiment of the invention, is adapted to make electric contact with the binding posts 16 carried by the disk and whereby an electric current may be completed while the bridge is in such contact.

As a means to cause the arm 13 to swing toward the disk and thereby complete the circuit as above described, I show an armature 17 mounted in any convenient manner upon the outside of the window pane or other support and which is adapted to be pressed toward the support far enough to cause coöperation between it and the magnet 12 with the result that the magnetism will cause the magnet and the arm 13 to be drawn toward the armature so long as the armature is pressed into close contact with the support 11. As a convenient means to so support the armature I provide a flexible cup 18 which may be cemented or otherwise secured to the surface of the support opposite that to which the disk is secured.

Having thus described my invention, what I claim as new and desire to secure by Letters Patent is:—

1. In a device of the character set forth, the combination with a support, of a plate secured on one side of the support, an arm movably connected to said plate, a magnet carried by the arm, and an armature secured on the opposite side of said support and movable toward and from said plate.

2. In a device of the character set forth, the combination of a vertical support, a plate secured on one side of said support and having a face inclined from its upper edge downward toward said support, an arm pivoted at its upper end to the upper portion of the plate, a magnet carried by the arm, and hence spaced at its lower end from the lower portion of the plate, and an armature secured to the opposite side of the support from the plate and movable toward and from the same into and out of the magnetic field of the magnet.

3. In a magnetic switch, the combination of an imperforate support, a plate secured on one side of the support, a pair of contact points carried by the plate, an arm pivotally connected to the plate and adapted to bridge said contact points, a magnet carried by the arm, and an armature secured to the oppo-

site side of the support from the plate and movable into the magnetic field of the magnet, substantially as set forth.

4. In a device of the character described, 5 the combination of a support, an arm movable toward and from said support, a magnet rigidly secured to said arm, an armature on the other side of and movable toward and from said support, and a flexible cup 10 connected with said support and with said armature whereby said armature is held resiliently in position away from said support.

5. In a device of the character described, 15 the combination of a support, an arm movable toward and from said support, a magnet secured to said arm, an armature on the opposite side of said support to said magnet and movable toward and from said magnet

whereby both the magnet and the armature 20 are movable, and a flexible cup supporting said armature and secured to said support.

6. In a device of the character described, the combination of a support, an arm movable toward and from said support, a magnet 25 mounted on said arm, an armature on the opposite side of said support to said arm and in line with said magnet, and a collapsible supporting cup secured to said support and supporting said armature regardless of 30 the position thereof.

In testimony whereof I have signed my name to this specification in the presence of two subscribing witnesses.

CLIFFORD G. MILLER.
